DISPLAY STAND FOR CLOTHES OR THE LIKE

Michael Naglowsky, 709 Walnut St., Erie, Pa. 16502

Filed Aug. 1, 1969, Ser. No. 18,506

Term of patent 14 years

Int. Cl. D6—01

U.S. Cl. D80—9

FIG. 1

FIG. 1 is a top plan view of a display stand for clothes or the like showing my new design; and

FIG. 2 is a side elevational view thereof, the support column being broken away to indicate indeterminate height.

The broken line illustration of garments in FIG. 2 is for purposes of illustration only.

I claim:

The ornamental design for a display stand for clothes or the like, as shown and described.
